MULTIPLE COMPARTMENT TRAY

Henry Hays Crimmel, Hartford City, Ind., assignor
or to Sneath Glass Company, Hartford City,
Ind., a corporation

Application January 27, 1938, Serial No. 187,107

4 Claims. (Cl. 62—1)

This invention relates to a universal purpose multiple compartment tray structure for refrigerators, or the like.

The chief object of the present invention is to provide in a tray structure a plurality of compartments one of which is of open or uncovered character and the other of which is covered so that whatever is in the covered compartments will not take up food odors from the refrigerator.

10 The cover compartment arrangement furthermore is adapted to contain cool water for drinking purposes and the cover prevents accidental contamination thereof by drippage in the defrosting of the cooling unit of the mechanical refrigerator or drippage therein in the event some other adjacent or superposed container happens to be accidentally tipped over.

15 It is contemplated to form the invention in such shape that it not only may be supported upon a rack or tray but may, if, as and when desired be associated with suspending guides or sideways.

20 In a multiple compartment tray of this character it is possible to retain ice cubes in the open storage and cool liquids for drinking purposes in the covered and dispensing portion of the tray.

25 One feature of one form of the invention is the ventilating character of the tray structure partition which renders the same suitable for ice cube storage and liquid cooling without melting of the ice cubes by the warm liquid in the dispensing compartment.

30 The full nature of the invention will be understood from the accompanying drawing and the following description and claims:

35 In the drawing Fig. 1 is a front to rear sectional view of a portion of a refrigerator with the multiple compartment tray suspendingly supported therebetween.

40 Fig. 2 is a front elevation of the same.

Fig. 3 is a top plan view of the multiple compartment tray structure shown in Figs. 1 and 2.

45 Fig. 4 is a transverse sectional view taken on line 4—4 of Fig. 3 and in the direction of the arrows.

Fig. 5 is a transverse sectional view taken on line 5—5 of Fig. 4 and in the direction of the arrows.

50 In the drawing 10 indicates the top portion of a mechanical refrigerator or the like, having, for example, the rear wall structure 11 and in which is mounted a refrigerating unit 13. Suitably secured to the refrigerator structure is the rack or like support 14 with which is associated 55 the depending angular members 15 for slidably

and suspendingly supporting a tray structure embodying the invention. The tray structure embodying the invention may also rest upon a rack structure, conventional in the refrigerator art.

Reference will now be had more especially to Figs. 3 to 5, inclusive, wherein there is illustrated one and the preferred embodiment of the invention. It includes a pair of opposite walls 16 and 17, a connecting wall 18 and another connecting wall 19. Each of these walls includes a rim portion 20 and the rim is substantially co-extensive with the top edges of these walls. 21 indicates the bottom portion of one compartment in the tray structure. 22 indicates another bottom portion and of the covered compartment portion of the tray structure.

25 In one form of the invention bottoms 21 and 22 may be continuations of the other. Projecting upwardly from the bottom portion, or portions, is a partition or ridge structure which defines the two compartments. This in the preferred form of the invention includes the wall portion 24 opposite the wall portion 18 and the wall portion 23 opposite the wall portion 19. This in the present invention, as illustrated clearly in Fig. 4, provides a space 25 between the exterior surfaces of the partition forming walls 23 and 24. If desired, these two walls 23 and 24 may be transversely united together between the walls 16 and 17 by the transverse web portions 26. This forms passageways in the partition wall and the partition walls at the junction 27 may be provided with apertures 28.

30 The closed compartment is provided with a suitable valve controlled drain structure 29, whereby said compartment may be drained. The upper edges of the wall portions 16 and 17 between the walls 23 and 19 and the upper edges of the walls 23 and 19 may have formed therein 35 a groove or seat 30. This is continuous about the top edge of the compartment.

35 A cover structure 31 includes a finger gripping portion 32 therein and forms a closure for the compartment described when it rests on the seat 40 45 50

All of the foregoing tray structure with the exception of the valve controlled outlet 29, may be of glass and the multiple compartment tray portion proper may be of integral character as illustrated.

55 As previously suggested, the uncovered compartment is adapted to receive vegetables, ice cubes, and the like, while the covered compartment is adapted to receive fruit juices, water, or

the like, for cooling purposes. Also, this covered compartment may receive odoriferous products in place of liquids to be chilled, in which event, of course, the valve controlled outlet would not necessarily be required for use. It is thus possible to maintain ice cubes in storage in the uncovered tray compartment and cool water for drinking purposes in the covered tray compartment and have the drinking water protected against accidental contamination in the event the refrigerating unit 13 accidentally defrosts, which does occasionally happen.

The invention furthermore has the advantage that as the drinking water is exhausted from the covered compartment, it may be refilled, and inasmuch as wall 23 is throughout a major portion of its length separated from wall 24 by the air passages 25, the warm water for replenishing the drinking water supply will not cause the rapid melting of ice cubes stored in the open compartment and furthermore, the cooling water may be more rapidly cooled by reason of this air circulation.

While the invention has been illustrated and described in great detail in the drawing and foregoing description, the same is to be considered as illustrative and not restrictive in character.

The several modifications described herein as well as others which will readily suggest themselves to persons skilled in this art, all are considered to be within the broad scope of the invention, reference being had to the appended claims.

35 The invention claimed is:

1. A multiple compartment tray structure,

adapted to be suspended within a refrigerator and the like, having a bottom common to each compartment, side walls integral therewith, an apertured ridge for compartment formation extending from one side wall to an opposite side wall, said ridge being formed by an indentation of said bottom, and web means between the sides of said ridge and integral therewith, said means providing with the apertures in said ridge a plurality of vertical air passages.

2. A tray structure for a refrigerator having integral side walls, a bottom integral with said side walls, an apertured ridge for compartment delineation formed by an indentation in said bottom, the sides of said ridge constituting additional side walls, and a plurality of webs integral with said additional side walls and providing with the apertures in said ridge a plurality of vertical air passages.

3. A refrigerator tray having a plurality of four-sided compartments, a bottom common to said compartments, said bottom being indented to form the fourth side of each compartment, an apertured compartment-delineating ridge likewise formed by the indentation of said bottom, and a plurality of webs integral with said fourth side of each compartment providing with the apertures in said ridge a plurality of air passages.

4. In a tray of multiple compartment character, a bottom common to each compartment, said bottom being indented to form a side of each compartment and an apertured ridge for compartment delineation, and web means between said sides providing with the apertures in said ridge a plurality of air passages.

HENRY HAYS CRIMMEL.
